(57) CLAIM

The ornamental design for an art supply organizer, as shown and described.

DESCRIPTION

FIG. 1 is a perspective view of an art supply organizer in accordance with the present design;

FIG. 2 is a front elevational view of the art supply organizer of FIG. 1;

FIG. 3 is a rear elevational view of the art supply organizer of FIG. 1;

FIG. 4 is a left side view of the art supply organizer of FIG. 1;

FIG. 5 is a right side view of the art supply organizer of FIG. 1;

FIG. 6 is top plan view of the art supply organizer of FIG. 1; and,

FIG. 7 is a bottom plan view of the art supply organizer of FIG. 1.

The broken lines in the drawings show portions of the art supply organizer that form no part of the claimed design.

1 Claim, 7 Drawing Sheets
